FIG. 1

FIG. 3

FIG. 2

FIG. 5

FIG. 4

UNITED STATES PATENT OFFICE

CHARLES H. ARNOLD, OF DAYTON, OHIO, ASSIGNEE, BY MESNE ASSIGNMENTS, TO THE NATIONAL CASH REGISTER COMPANY, OF DAYTON, OHIO, A CORPORATION OF MARYLAND

CASH REGISTER

Application filed June 5, 1924. Serial No. 718,046.

This invention relates to cash registers, and more particularly to the totalizer mechanism thereof.

One object of this invention is to provide an adding and subtracting totalizer for use with cash registers, which totalizer is more compact and practical than those now in use.

Another object is the construction of an adding and subtracting totalizer whose units can be readily assembled and placed in the machine, or assembled in position in the machine.

Another object is the construction of an adding and subtracting totalizer requiring a small amount of movement between adding and subtracting positions.

With these and incidental objects in view, the invention consists of certain novel features of construction and combinations of parts, the essential elements of which are set forth in appended claims and a preferred form or embodiment of which is hereinafter described with reference to the drawing which accompanies and forms part of this specification.

Of said figures:

Fig. 1 is a front elevation of one of the totalizer lines, carrying three adding and subtracting totalizers and a single adding totalizer, together with the cam for shifting the totalizer line and the actuating racks for operating the totalizer wheels.

Fig. 2 is an enlarged detail view of one of the adding and subtracting units.

Fig. 3 is an enlarged perspective view of one of the adding and subtracting units with part of the mechanism thereof broken away.

Fig. 4 is a detail sectional view taken substantially on the line 4-4 of Fig. 2 looking in the direction of the arrows.

Fig. 5 shows the two connecting pinions between the adding and subtracting totalizer wheels, and the member which supports them.

General description

This invention is shown embodied in a machine of the type shown and described in Letters Patent of the United States to F. L. Fuller, No. 1,242,170, granted Oct. 9, 1917,

and therefore only such of the mechanism as is considered necessary properly to show the operation of the invention is included in this application.

In the Fuller patent above mentioned there is shown an adding and subtracting totalizer including two ordinary totalizer wheels, such as is usual in these machines, having bevel gears fastened to their adjacent sides. There are two bevel pinions shown which mesh with both of the bevel gears so that movement of one of the totalizer wheels will rotate the other one of the pair in the opposite direction.

The above mentioned construction, as shown in the Fuller patent, necessitated the spacing of the adding and subtracting wheels a sufficient distance apart to provide room for the bevel gears and pinions which co-operate with both wheels. This spacing had to be so great that it was possible to put only one adding and subtracting totalizer onto a totalizer line, such as is well known in these machines. In the present invention, however, a construction is provided which permits the adding and subtracting totalizer wheels to be placed close together, thereby allowing a plurality of adding and subtracting totalizers to be mounted on the same totalizer line.

In Fig. 1 it will be noted that there are three adding and subtracting totalizers and one adding totalizer all mounted on the same line. Such an arrangement is extremely useful, as it triples the number of adding and subtracting totalizers that can be successfully used in machines of this character.

Construction of adding and subtracting totalizer units

Each of the adding and subtracting units consists of an adding wheel 30 and a subtracting wheel 31. These wheels are loose on a tube 32, supported at its right hand end (Fig. 1) by a bracket 33, and at its left hand end by a bracket 34, both slidably mounted on a shaft 35 slidably mounted in the usual cam plates 36 (one only shown) secured to the machine side frames 37. Secured to the adjacent sides of the wheels 30 and 31 are

gears 38 and 39 (Fig. 3). Between the gears 38 and 39 is a ring 40 which carries an interiorly projecting lug 41 cooperating with a spline 42 in the tube 32. This construction permits the endwise movement of the ring 40 on the tube to assemble the ring on the tube, but prevents any rotating movement about said tube during operation of the machine. The ring 40 has an extension 43 (Fig. 5) which carries a pin 44, on which is loosely mounted a pinion 45. The extension 43 also carries a pin 46 on which is loosely mounted a pinion 47. The extension 43 is wider than the ring 40 and is counterbored on opposite sides at 48 and 49 to receive the pinions 45 and 47 respectively. The pinion 45 is located to mesh with the gear 38, and is held from lateral movement by the adding wheel 30. The pinion 47 is located to mesh with the gear 39, and is held from lateral movement by the subtracting wheel 31. These pinions 45 and 47 are of sufficient width to mesh with each other at the place where the counterbored holes overlap or communicate with each other. It can be seen from Fig. 3 that if the adding wheel 30 is rotated clockwise, the pinion 45, which meshes with the gear 38, will be rotated counter-clockwise, the pinion 47 which meshes with the pinion 45 will be rotated clockwise, and the gear 39 and subtracting wheel 31 will be rotated counter-clockwise, that is, in the opposite direction from that of the adding wheel 30. Thus any movement given to one of the two wheels 30 or 31 will rotate the other wheel of the pair in the opposite direction to the same extent.

Shifting mechanism

40 As above mentioned, all of the adding and subtracting totalizer wheels are loosely mounted on the tube 32, and the means for shifting this tube and the totalizer wheels laterally to position any desired set of totalizer 45 wheels in a position to cooperate with a plurality of actuating segments 50 (Fig. 1) will now be described. The bracket 34, which supports the left hand end of the tube 32, carries a boss 51 in which is mounted a rod 52 carrying flanged rollers 53. The lower roller 53 operates in a cam slot 54 formed in a segmental cam 55 fast on a sleeve 56 supported by a stud 57 carried by the side frame. Upon the operation of the machine, the cam 55 is 55 differentially positioned under the control of the keys in the control bank appropriate to the particular totalizer line to be operated, as fully disclosed in the patent referred to. The control bank (not shown) of this machine includes three sets of adding and subtracting 60 keys, one set for each adding and subtracting totalizer. The conformation of the cam 55 is such that the brackets 33 and 34 and the tube 32 carrying the totalizer wheels will be shifted to and fro laterally of the machine, de-

pending upon which totalizer is to be operated and whether it is to be an adding or a subtracting operation. The parts are guided in their lateral movements by a slotted angular bracket 58 projecting laterally from the side frame of the machine and having a slot 59 formed therein in which the upper roller 53 operates.

When an adding key is depressed, the cam 55 will cause the adding totalizer wheels of the corresponding totalizer to be positioned in alignment with the actuating segments 50, and if a subtracting key is depressed the cam will cause the subtracting wheels 31 of the corresponding totalizer to be moved into alignment with the actuating segments 50. It can be seen from Fig. 1 that the single adding totalizer is in alignment with the actuating segments. This totalizer is mounted on this totalizer line, in addition to the adding and subtracting totalizers.

After the totalizer wheels have been positioned, in accordance with the control key depressed, they are moved into engagement with the actuators. The means for effecting this engagement is very well known and is described in the above mentioned Fuller patent, and therefore no showing or description thereof is included herein. A stationary aliner 60 is provided for each totalizer line. These are identically the same as the aliners shown in the Fuller patent with the exception that a plurality of notches 61 are formed in said aliners to permit either the adding or subtracting wheel to rotate when the other wheel of the pair is driven.

While the form of mechanism herein shown and described is admirably adapted to fulfill the objects primarily stated, it is to be understood that it is not intended to confine the invention to the one form or embodiment herein disclosed, for it is susceptible of embodiment in various forms, all coming within the scope of the claims which follow.

What is claimed is:

1. An adding and subtracting totalizer including adding and subtracting elements, means operatively connecting said elements and means including the adding and subtracting elements to hold the connecting means in functioning position.

2. An adding and subtracting totalizer including adding and subtracting wheels, a member for supporting the same, pinions connecting said wheels, a plate non-rotatably mounted on said member for supporting said pinions, means for holding said wheels against longitudinal movement on said member, the parts being arranged so that each adding and subtracting wheel retains its respective pinion on said plate.

3. In an adding and subtracting totalizer; the combination of a single non-rotatable shaft, totalizer elements rotatably mounted on the shaft; a non-rotatable support between

the totalizer elements in position to contact the adjacent sides of both totalizer elements; and intermeshing pinions rotatably mounted on the support and held against axial movement by the support and the totalizer elements, said pinions also meshing with the totalizer elements to rotate the totalizer elements in opposite directions when either element is rotated in either direction.

10 In testimony whereof I affix my signature.
CHARLES H. ARNOLD.
